ROUGHING MACHINE

Charles G. Brostrom, Salem, Mass., assignor to
 United Shoe Machinery Corporation, Borough
 of Flemington, N. J., a corporation of New
 Jersey

Application March 30, 1938, Serial No. 198,950

8 Claims. (Cl. 12—17)

This invention relates to roughing machines and is herein illustrated as embodied in a machine for roughing channels and channel lips formed in shoe soles.

5 It is an object of the invention to provide a channel roughing machine of simple construction which will operate easily and effectively upon both the base and lip of a channel with a minimum of preliminary preparation of the
 10 channeled sole.

With channel roughing machines heretofore in use it has been necessary to raise and turn back the lip of the channel before presenting the sole to the machine. One of the features
 15 of the present invention consists in the provision of means for opening the channel in advance of the roughing tool so that no preliminary lip raising operation is necessary and a shoe may be operated upon immediately after
 20 the sole has been laid. As shown herein, the channel opening means may consist of a plow adapted to enter beneath the channel lip and arranged to oscillate transversely of the channel, preferably about its point or free end as a
 25 center.

In accordance with another feature of the invention the channel opening means is so mounted and retained as to permit it to be moved instantly into or away from operating relation
 30 to the roughing tool in order to adapt the machine for operation upon either soles the channel lips of which have previously been raised or those of which the lips have not been raised.

A further feature of the invention consists in
 35 the provision of an improved roughing tool, preferably a wire brush, having the form of a pointed cone adapted to be received within a sole channel and to engage the channel base and the inner surface of the lip simultaneously. All
 40 parts of the periphery of such a tool can operate upon both the base and the lip when the lip is properly supported, and the vertical angle of the cone may be acute, so that it is not necessary to bend the lip back in order to operate
 45 effectively upon it.

These and other features of the invention, including certain details of construction and combinations of parts, will now be described in greater detail in connection with the accompanying
 50 drawings, in which

Fig. 1 is a view, in front elevation, of a machine embodying the invention;

Fig. 2 is a view, in side elevation, of the upper portion of the machine;

55 Fig. 3 is a view, in side elevation, showing

the relation between the roughing tool and the plow;

Fig. 4 is a view, partly in front elevation and partly in vertical section, of the roughing mechanism and the channel lip support;

Fig. 5 is a plan view taken on the section line V—V of Fig. 2;

Fig. 6 is a detail view of the roughing brush;

Fig. 7 is a view, in front elevation, of the brush sharpening mechanism;

10 Figs. 8 and 9 are a front elevation and a plan view, respectively, of a modified form of plow oscillating mechanism; and

Fig. 10 is a detail view showing the manner in which the work is presented to the machine. 15

Referring to Fig. 1, the illustrated machine is provided with a base 12 containing bearings 14 for a shaft 16 to which is secured a pulley 18 driven from any suitable source of power. Also secured to the shaft 16 is a pulley 20 connected 20 by a belt 22 to a pulley 24 affixed to a countershaft 26. Also affixed to the countershaft 26 is a driving pulley 28 which is connected by a belt 30, passing around idle pulleys 32, to a driven pulley 34 upon a roughing tool spindle 36. 25

The spindle 36 (see Fig. 4) is hollow and is mounted to run in ball bearings 38, 40 which are seated in the upper and lower ends respectively of a normally stationary head 42 carried by a horizontal, cylindrical tube 44 which is 30 clamped in the upper section 46 of the frame of the machine.

The roughing tool, which is best illustrated in Figs. 4 and 6, comprises a bundle of wire bristles 48 which are confined closely in a metal tube 50. 35 The tool thus consists of a wire brush the lower end of which may be ground to the form of a pointed cone, as shown at 52, the tube 50 being ground away as the brush is reground from time to time to sharpen it and preserve its shape. The tube 50 has a snug, sliding fit in a slit bushing 54 which, in turn, is adapted to be inserted in the hollow spindle 36, the lower end of which is formed to provide a chuck 56 which may be tightened upon the slit lower end portion of the 40 bushing 54, causing the latter to grip and hold the roughing brush after the latter has been adjusted vertically to the desired position.

The vertical angle at the tip of the roughing brush is preferably somewhat acute, as shown, 50 in order that all parts of the periphery of the tool may operate upon both the base and the lip of a sole channel without requiring that the lip be turned back over the tread face of the sole.

In order to hold the channel lip up to the 55

roughing tool I have provided a lip support consisting of a frusto-conical roll 58 which is mounted to rotate freely upon a screw 60 threaded into the end of an adjustable arm 62 mounted to 5 swing about the axis of a pair of pointed screws 64 threaded through lugs 66 projecting from the head 42 (see Figs. 2 and 4). The point of a stop screw 68 threaded through the arm 62 engages a protuberance 70 upon the head 42 and 10 adjustably limits the approach of the lip supporting roll 58 to the roughing tool.

One end of a link 72 is pivotally connected at 74 to the arm 62 and the other end of said link is pivotally connected at 76 to a lever 78 movable 15 about a stationary pivot 80. A pull spring 82 tends to draw the upper end of the lever 78 toward the right, as seen in Fig. 1, and consequently to move the lip supporting roll 58 toward the roughing tool. The lower end of the lever 20 78 is engaged by the upper arm of a bell crank lever 84, the lower arm of which is connected by a treadle rod 86 to a treadle 88 in such a manner that depression of the treadle will cause 25 the lip support to be moved away from the roughing tool, to permit the channel portion of the shoe sole to be presented thereto.

In order to aid in the presentation of a shoe 30 to the machine and the control of the shoe as it is moved past the roughing tool, a thumb rest 90 is provided. The shank portion 92 of this thumb rest is secured by a set screw 94 in a bracket 96 fastened to the lower end of the head 42.

The mechanism for raising the channel lip, to 35 open the channel in advance of the roughing tool, comprises a plow 98 which is clamped in a holder 100 mounted upon an arm 102. The end of the arm 102 remote from the plow holder 100 is supported very loosely by a stationary stud 40 104, so that the arm, resting upon the head of the stud, is capable of universal movement to a limited extent and can rock freely in all directions sufficiently to impart the desired movement to the plow.

45 A pin 106, projecting from the plow holder arm, is adapted to engage in a hole near the end of a spring finger secured by a screw 110 to a stationary bracket 112 which is fixed upon the thumb rest shank 92 by a set screw 114 and, 50 when the parts are set as shown in Fig. 5, the arm 102 and the plow carried by it are capable of oscillation about an imaginary line, or axis, passing through the pin 106 and the stud 104. When it is not desired to use the channel 55 opening plow the spring finger 108 is pushed off the pin 106, whereupon the plow may be instantly swung around the stud 104 to an inoperative position, out of the way as shown in dotted lines in Fig. 5.

60 The oscillation of the plow is effected by a cam 116 which is screwed upon the spindle 36, as best seen in Fig. 4. A cam roll 118 upon the plow holder arm 102 engages in the cam 116 and causes the plow to perform a complete oscillation during 65 each revolution of the said spindle.

In Figs. 8 and 9 is shown an alternative form of plow operating mechanism in which the plow is oscillated about its point or free end as a center. In this form, instead of the cam 116, a 70 pulley 120, mounted upon the spindle 36, drives a belt 122 which passes around a driven pulley 124. The pulley 124 is affixed to a shaft 126 rotatable in a bearing 128 supported by a frame 130. Also affixed to the shaft 126 is a crank disc 132 having a crank pin 134 from which motion

is transmitted by a connecting rod 136 to an arcuate slide 138. A channel lip raising plow 140 is rigidly secured to the slide 138 and partakes of the movement of the latter. The slide 138 is movable upon a semi-circular guide 142 5 the center of which is substantially at the point or free end of the plow so that the plow oscillates about its free end as a center. The guide 142 has a shank portion 144 which is secured by a screw 146 to the frame 130, to provide a rigid 10 support for the guide.

An arm 148, integral with the frame 130, is supported by the stationary pin 104 and the frame is provided with a pin 150 for engagement with the spring finger 108 as in the first described 15 form of the invention, except that the arm 148 is fitted closely upon the pin 104 so that the frame 130 cannot rock, but can be swung aside 20 out of the way when the spring finger is disengaged from it.

In order to form the tip of the roughing tool 25 52 to the desired angle and to resharpen it from time to time as it becomes dull or deformed, a grinding attachment is provided, as shown in Figs. 1, 2 and 7. Supported by a bracket 152 at the right-hand side of the machine frame is a bearing 154 in which runs a shaft 156 carrying a pulley 158 which is driven by a belt 160 from a pulley 162 upon the countershaft 26. The pulley 162 is adapted to be connected to and disconnected from the countershaft by a clutch controlled by a knob 164 (see Fig. 1).

The left-hand end of the shaft 156 runs in a bushing 166 mounted in a sleeve 168 (Fig. 7) which is both rotatable and longitudinally slideable in a stationary bearing 170 bolted upon the head 42. The end of the sleeve 168 is flanged at 172 and a pulley 174 pinned to the shaft 156 has an annular retainer 176 which embraces the flange and prevents axial movement of the pulley relatively to the sleeve but permits the pulley to rotate freely thereon.

Clamped upon the sleeve 168 by screws 178 is an arm 180 which carries the grinder. In order to facilitate exact adjustment of the grinder 45 toward and from the roughing tool, the sleeve 168 is surrounded by a compression spring 182 which holds the end of the sleeve against an adjusting screw 184 threaded through a bracket 186 which is bolted to the bearing 170, the adjustment, after it has been effected, being maintained by a locknut 188.

The end portion of the arm 180 is formed to provide an arcuate guide 190, the center of curvature of which is at approximately the tip of 55 the roughing tool 52. Adjustably secured to this guide by a bolt 192 is a grinding wheel carrier 194 in which runs a shaft 196 upon which is mounted an abrasive wheel 198.

Also affixed to the shaft 196 is a pulley 200 60 driven by a belt 202 which passes around idle pulleys 204 and the driving pulley 174 upon the shaft 156. The pulleys 200 and 204 are covered by a belt guard 206 upon which is a handle 208 by means of which the grinding apparatus 65 may be swung into and out of operative position.

By adjusting the carrier 194 along the guide 190 the tip angle of the roughing tool may be changed, if desired, to conform to the beveled end 210 of a gage 212 which is hinged at 214 to an arm 216 mounted to swing around a stationary post 218, so that when the gage is not in use it may be folded over and swung aside out of the way.

In operation, the lip supporting roll 58 is 75

5 moved away from the roughing tool by depressing the treadle 88 and the shoe is presented to the machine with the plow 98 between the lip and the channel base. The treadle being released, the lip will be supported against the action of the roughing tool by the roll 58 and the shoe will be moved by the operator in the direction indicated by the arrow A in Fig. 10, the oscillating plow raising the channel lip ahead of 10 the roughing tool sufficiently to permit the latter to operate simultaneously upon both the lip and the channel base from one end of the channel to the other.

15 Having described the invention, what is claimed as new and desired to be secured by Letters Patent is:

20 1. A machine for operating upon channeled soles, comprising a roughing tool adapted to operate in the channel of a sole, means for opening the channel in advance of said roughing tool, a pivotal mounting about which the channel opening means may be swung into or away from operating relation to the roughing tool, and an instantly manually releasable retainer for holding 25 said channel opening means in operating position.

25 2. A machine for operating upon channeled soles, comprising a roughing tool adapted to operate in the channel of a sole, and an oscillatory plow positioned in advance of said roughing tool to open the channel.

30 3. A machine for operating upon channeled soles, comprising a roughing tool adapted to operate in the channel of a sole, a channel opening plow positioned in advance of said roughing tool and having a free end adapted to extend into the channel, and means for oscillating said channel opening plow about said free end as a center to open the channel.

4. A machine for roughing sole channels, comprising a roughing tool adapted to operate in the channel of a sole, an oscillatory channel opening plow positioned in advance of said roughing tool and having a free end adapted to extend 5 into the channel, and means for oscillating said plow transversely to the channel.

5. A machine for roughing channels and channel lips on shoe soles, comprising a pointed, conical roughing tool adapted to be received within 10 a channel, and means for rotating said tool about its conical axis, whereby the periphery of the tool will engage simultaneously the base of the channel and the inner surface of the lip.

15 6. A machine for roughing channels and channel lips on shoe soles, comprising a pointed, conical roughing tool adapted to be so received within a channel that all parts of the periphery of the tool will operate upon both the base and the lip of the channel, and a channel lip support so 20 related to said tool that the tool will operate simultaneously upon both the base and lip of a channel when the lip is positioned against the support.

25 7. A roughing machine comprising a channel lip support in combination with a wire brush in the form of a pointed cone with its point adjacent to said lip support, and means for rotating said brush about the axis of the cone.

30 8. A roughing machine comprising a channel 30 lip support in combination with a tubular rotary spindle, and a bundle of wire bristles secured within said spindle and extending from an end thereof, the extending portion of said bundle being in the shape of a cone coaxial with 35 said spindle.

CHARLES G. BROSTROM.
